UNITED STATES PATENT OFFICE.

GEORGE RIVOIRE, OF STAPLETON, NEW YORK.

FRAME HOLDER.

Application filed February 21, 1925. Serial No. 10,908.

This invention relates to frame holders or similar holding devices employed in conjunction with canopy or awning frames for permitting or preventing movement of the 5 movable section of such frames.

There are canopy or awning frames which consist of a fixed section and a movable section which has compound movement with respect to the fixed section. It is with this 10 particular type of canopy or awning frame sections that one or more of the devices of the present invention is used in conjunction with.

An object of the present invention is to 15 produce a comparatively simple, efficient and effectual holding device for preventing the bodily upward movement of the movable frame section of an awning framework when disposed in its active position and which also 20 serves to permit the bodily upward movement of said section when the device is released from securement with the relatively fixed frame section.

Other objects of the invention will appear 25 when the following specification is read in conjunction with the accompanying drawing, in which—

Figure 1 is a fragmentary side elevation of a canopy or awning including the usual 30 fixed and relatively movable frame sections with the device of the present invention actively applied thereto.

Fig. 2 is an enlarged sectional elevation of the device actively applied and in which 35 fragments of the fixed and relatively movable frame sections are shown.

Fig. 3 is a sectional view taken on the line 3—3 of Fig. 1 looking in the direction of the arrows.

By referring now to Fig. 1 of the drawing 40 it will be apparent that the device 10 of the present invention is shown applied in operative relationship with an awning or canopy 11. The awning 11 in the present instance includes a fixed frame section including 45 vertically disposed rods 12 attached usually at opposite sides of a window opening, and a relatively movable frame section including side rods 13 pivotally connected as at 50 14 to a sleeve 15 arranged for sliding movement on the rods 12 respectively. The frame sections carry the usual canopy or flexible shade 16 and pull ropes 17 attached to the movable frame section are employed for elevating said section. Under ordinary conditions when it is desired to elevate the mov-

able frame section the free ends of the rope 17 are pulled downwardly which causes the rods 13 to pivot until they reach a substantially vertical position whereupon the movable 60 frame section including the sleeves 15 is raised bodily. The ends of the rope 17 are then tied to hold the movable frame section in its elevated position.

In order to hold the movable frame section in its horizontally disposed position when the same is let down for the shading condition of the canopy against movement either bodily or pivotally, there is provided the device 10 which comprises a sleeve 18, 65 latch or yoke 19, and fastening means 20. The sleeve 18 is provided with spaced lugs 21 having aligned apertures therein to accommodate a bolt 22 which passes through the apertured part 23 of the latch to effect 70 the pivotal connection of the latter. The means 20 is in the nature of a set screw having a manipulating head 24 and adapted for threading in either of the screw threaded holes 25 in the sleeve 18. It is to be understood 75 that one or two devices 10 may be employed and as employed the sleeve 18 of each device will surround one of the rods 12 and be slidable thereon except when the screw 20 is manipulated to bring the inner end 80 thereof in contact with the rod 12. As shown in Fig. 1 the device 10 is in active condition in which the sleeve 18 is held on the rod 12 against movement and the latch 19 is disposed in locking engagement with the rod 13 85 beyond its pivot point 14. Under this condition the movable frame section is prevented from having either pivotal or bodily upward movement. It, therefore, follows 90 that the canopy 16 will be held taut at all 95 times and the movable section will be prevented from rattling. When it is desired to raise the movable section to fold the canopy 16 the screw 20 is loosened, the sleeve 18 is elevated slightly to allow the latch to clear 100 the rod 13, and the device in its entirety is turned about the rod 12 to a position as shown for instance in Fig. 3 in dotted lines, whereupon the movable frame section may be readily elevated as will be understood. 105 It is to be understood that as the movable frame section is being elevated the holding device 10 rides up idly on the rod 12 by virtue of the contact established between the sleeves 15 and 18.

I claim:

1. The combination with a framework in-

cluding a relatively stationary section and a relatively movable section; of a holding device including a bodily movable member removably engageable with said movable section, and means for holding said member fixed to said stationary section to prevent the movement of the movable section when said member is in engagement therewith.

2. The combination with an awning framework including a relatively stationary rod and a member connected to said rod for compound movement with respect thereto; of a holding device slidably mounted on said rod, said device including a latch movable into and out of engagement with said member to prevent the movement of said member when said device is held against movement and to permit the movement of said member when said device is free to move, said device also including means for permitting

or preventing the movement of the device on said rod.

3. A holding device comprising a sleeve, fastening means carried by said sleeve, spaced lugs extending radially from said sleeve, and a yoke movably carried by said lugs, said yoke capable of saddling a member extending radially with respect to the longitudinal axis of said sleeve. 25

4. A holding device comprising a sleeve, fastening means carried by said sleeve, a yoke capable of saddling a member extending radially with respect to the longitudinal axis of said sleeve and having a portion arranged between said lugs, and a bolt extending through said lugs and said portion arranged therebetween to effect the pivotal connection of the yoke to said sleeve. 30 35
